UNITED STATES PATENT OFFICE.

RUBY R. HAWK, OF CHICAGO, ILLINOIS.

MEAT RAIL AND HOOK.

1,294,457.

Specification of Letters Patent. Patented Feb. 18, 1919.

Application filed March 21, 1918. Serial No. 223,763.

To all whom it may concern:

Be it known that I, RUBY R. HAWK, a citizen of the United States, residing in Chicago, county of Cook, and State of Illinois, 5 have invented certain new and useful Improvements in Meat Rails and Hooks, of which the following is a specification.

My invention relates to hooks and their mounting for hanging meat in refrigerator 10 or other cars, or the like. The object of my improvement is the provision of simple and efficient supporting means for supporting meat and the like in refrigerator or other cars, or in other storing places. A further 15 object is the provision of meat hooks and their mounting, which are not too easily detached from their mountings, so as to be easily displaced, but which can be quickly and easily taken from the supports for cleaning, 20 and the like, when so desired. A still further object is the provision of supporting means for meat hooks, and bracing and supporting means for said supporting means. Other objects will appear hereinafter.

25 An embodiment of my invention is shown in the accompanying drawing forming a part of this specification, and in which—Figure 1 is a fragmental, transverse section of a car equipped with my invention; Fig. 2 is 30 a fragmental longitudinal view of the same; and Fig. 3 is a transverse section of a beam used in the construction, with my improved hook mounted thereon.

Referring more particularly to the drawing, I have indicated a car by the side walls 35 5, end wall 6, roof 7 and carlines 8. These parts may be of any preferred or conventional design, as my invention is adapted to be applied to all makes of refrigerator or 40 other cars used in the transportation of meats and the like.

I preferably provide brackets 9 which are secured to the walls 5 by nails 10 or any other desirable means. The brackets 9 are 45 preferably U-shaped, with their top portion open, so that beams 11 may be inserted in the tops of such U-shaped members and supported thereby against all movements except upward movements. The U-shaped 50 members 9 may be formed in any preferred shape, but in order to make them light and strong I prefer to form a ridge-like portion 12 around the opening of the member and provide webs 13, as indicated in Fig. 2, to 55 strengthen the part 12.

I preferably arrange the beams 11 cross-

wise of the car and provide any desirable number of such beams. Ordinarily about seventeen of these beams are used in a conventional refrigerator car. These beams 60 may be made up in any preferred manner, but in order to make a beam which is strong and light I preferably make them up using an inverted T-rail 14 of steel, and cut a groove longitudinally of a wooden bar 15 65 which snugly fits the T-rail substantially as indicated in Fig. 3. Two or more pins 16 may be placed through the T-rail and member 15, as indicated in Fig. 1, to hold such parts together. It will be noted that the 70 articles supported on the beam will tend to hold these members 14 and 15 together, but when they are removed from their operative position in the car, the pins 16 will keep them in their proper relations. In order to 75 prevent easily removing the beams 11, I preferably place a bolt or pin 17 through one end of each beam and its corresponding bracket 9, substantially as indicated in Fig. 1. It will be apparent, however, that a bolt 80 17 may be extended through the other bracket 9 and other end of the beam 11 when so desired. The purpose of this particular construction is that upon removing the bolt 17 the beam can be lifted up out of the brackets 85 9 and removed for cleaning or any other purpose desired, and yet with the bolt 17 in place the beams 11 are held sufficiently rigid in the car to prevent workmen from carelessly and easily displacing them. This 90 makes a construction which is easily removable when desired, and yet sufficiently secure to prevent loss of the parts.

Each of the beams 11 is provided with as many notches 18 as is desired. The notches 95 18 are provided so that hooks 19 which support the meat or other articles to be carried by the beams 11, will not slide along the beams as the car is moved along. The notches 18 may be eliminated if desired, 100 but I find it best to use them in order to keep the meat evenly distributed along the beams 11.

The hooks 19 are preferably provided in two or more lengths so that by hanging some 105 of the pieces of meat higher than others more can be stored in a car than where the hooks are all the same length. The length of the hooks may be varied to suit different requirements. Also the number of hooks on 110 the beams may be varied as desired. Each hook 19 has a shank 20 and a hook proper 21

at its lower end adapted to receive the meat or other articles. At its upper end is a loop, preferably formed having a U-shaped portion 22 which faces downwardly or in a general direction toward the hook 21, so that when the U-shaped portion 22 of the hook is engaging the beam 11, the shank 20 will be maintained in substantially vertical position. The loop is also provided with a substantially U-shaped portion 23 which is set so that the legs of the U-shaped portion 23 are at slightly obtuse angles to the legs of the U-shaped part 22. With this particular relation, when the U-shaped part 23 engages the beam 11, the shank 20 and hook 21 will take a position slightly above the U-shaped portion 22. The last-named position of these parts is shown by dotted lines in Fig. 3. The purpose of this is to move the hook 20 into a position where the point 21 will be out of the way when it is desired to use the car for other purposes than meats and the like. In the usual practice at this time, hooks are used which are easily detachable from their supporting rails and when the car is to be used for other purposes than meat and the like, such hooks are taken off and thrown in a corner and lost.

In this device, when the hooks are not in use, the U-shaped portions 23 are engaged on the beams 11 to hold the hooks up out of the way, and where there is very small danger of their injuring anyone passing under the beams 11.

On each beam 11, I place one or more, preferably two, castings 24 which are adapted to loosely fit the beam and slideable over it in order to make them removable from the beam. Each casting 24 is provided with two lateral ears 25, and between the lateral ears 25 of two adjacent castings 24 I place a brace 26. At the ends of the car I provide castings 24', one only being shown in Fig. 2. Each casting 24' is secured to the car by nails or lag screws 10' and provided with an ear 25 which is connected by means of a brace 26 to the ear 25 on the adjacent casting 24. The purpose of the braces 26 and castings 24 and 24' is to brace the beams laterally so that sudden lurches or jars of the car will not break the beams 11 when the latter are heavily loaded. When so desired, a turn-buckle 27 may be placed in the braces 26 so that easy and quick adjustments may be made in said braces if desired.

I find that it is also desirable to support the intermediate portions of the beams 11, and as a simple means for accomplishing this, I place a loop 28 at the top of each casting 24. It will be understood that a hook or other perforated member may take the place of the loop 28, when so desired, without departing from my invention. Above each loop 28 I provide a hook 29 which is anchored in a carline 8 in any de-

sired manner, such as by having a nut 30 threaded thereon and embedded in the carline. The form and shape of the hook 29 may be varied to suit different requirements. It is desirable to have the beam 11 placed at 70 a distance sufficiently below the carline 8 so that the beam may be lifted out of the brackets 9 before the loops 28 touch the bottom of the carlines or other parts of the top of the car. In order to remove the beams 11 75 from the brackets 9, such beams are raised straight up until they are freed from the brackets, then the beam turned over to disengage the loops 28 from the hooks 29, when such beams with the parts hanging thereon 80 can be taken down for cleaning or repairing.

While I have illustrated and described the preferred form of my invention, I do not desire to be limited to the precise details set forth, but desire to avail myself of such variations and changes as come within the scope of the appended claims.

I claim:

1. In combination, a car; supports on the vertical walls of the car; beams having their ends resting in said supports and adapted for vertical movements out of the supports; loop members connected to intermediate parts of the beams; hooks depended from the roof of the car and engaging said loop members; spacing bars between and connected to intermediate parts of the beams; and article-supporting hooks mounted on said beams.

2. In combination, a car; a plurality of spaced beams supported at their ends on the inner walls of the car; a member mounted intermediate the ends of each beam; spacing bars connecting the members; turn-buckles in said spacing bars for varying the lengths of the latter; supports extending between said members and the car roof; and article-supporting hooks mounted on said beams.

3. In combination, a car; U-shaped brackets on the vertical walls of the car; a beam having its ends resting in said U-shaped brackets; a member mounted on said beam; a loop on said member having its opening substantially as long as the depth of the opening in said U-shaped brackets; and a hook on the roof of the car engaging said loop.

4. In combination, a car; a plurality of spaced beams supported at their ends on the inner walls of the car; a member loosely mounted intermediate the ends of each beam; spacing bars connecting the members; supports extending between said members and the car roof; and hooks having portions extending around said beams.

5. In combination, a car; a plurality of spaced beams supported at their ends on the inner walls of the car; a member slidably mounted intermediate the ends of each beam; perforated ears on the lateral sides of said

members; spacing bars having their ends engaging the perforations of said ears spacing said members apart; supports connected with the roof of the car and attached to said members; and hooks having loops disposed around said beams.

6. In combination, two vertical walls and a top wall; U-shaped brackets on the adjacent sides of the vertical walls; a beam having its ends resting in said U-shaped brackets; a support having one portion secured to the top wall and another portion connected with an intermediate part of said beam, the portions of said support being adapted to be separated upon removal of said beam from said brackets.

7. In combination, two vertical walls and a top wall; U-shaped brackets on the adjacent sides of the vertical walls; a beam having its ends resting in said U-shaped brackets; a member loosely mounted on the intermediate part of the beam; an extension on said member having a perforation therein; a hook connected with the top wall and engaging the perforation of the extension on said member; and meat hooks on said beam.

8. In combination, a car; U-shaped brackets on the inner walls of the car; a

beam having its ends resting in said U-shaped brackets; a member slidably mounted on the intermediate part of said beam; a loop on said member; a hook connected with the roof of the car and engaging said loop, said beam being adapted for bodily vertical movement out of said brackets and for lateral movement to disengage said hook; and meat hooks mounted on said beam.

9. In combination, a car; U-shaped brackets on the inner walls of the car; a perforated member; a beam extending through the perforation of said member and having its ends resting in said brackets; a support made up of two portions detachably connected together, one portion being secured to the roof of the car and the other portion being attached to said perforated member, the portions of said support being separable upon the removal of the beam from said brackets; and meat hooks having loops engaging said beam and adapted for removal from the latter when such beam is removed from said brackets.

In testimony whereof I have signed my name to this specification on this 18th day of March, A. D. 1918.

RUBY R. HAWK.
